SHAVING DEVICE

John A. Hanley, Stamford, Conn., assignor, by
mesne assignments, to Clipshave, Inc., a corpora-
tion of New York

Application August 11, 1934, Serial No. 739,432

10 Claims. (Cl. 30—43)

My present invention relates to improvements in shaving devices, particularly to devices of the type in which a pair of relatively slideable shearing plates serve to clip the hair. More specifically the invention is concerned with a razor of the dry shave type which will permit the removal of a stiff stubbly beard without scratching, abrading or otherwise injuring even the most tender skin and which gives an exceptionally close shave due to the fact that it is inherently adapted for severing the hair at a point below the small circular mound of skin which surrounds it.

Objects of the invention are to provide a cutting apparatus of this type characterized by simplicity of construction, ease of manipulation, ruggedness and durability in use; to provide a device consisting of but few parts, which is devoid of tensioning springs or any parts apt to be broken or bent by careless handling; and to provide a device which cannot become clogged with hair during the shaving operation and is highly sanitary and efficient in use, light in weight and inexpensive to manufacture.

While it is to be understood that the invention may be embodied in a manually operated cutter for hair clipping or shaving purposes, the device finds its preferred embodiment in an electrically operated razor utilizing a pair of relatively reciprocating toothed shear plates.

A feature of the invention is the use of means on one plate which guards the skin from contact with the operative edges of the cutters. Such means is preferably formed by turning over the ends of the teeth on one cutter member. These bent over teeth are devoid of corners or projections. They ride on the surface of the skin and act to depress the small mounds of flesh which encircle each whisker, and insure a close cut without injuring the skin.

Another feature of the invention is the use of two shear plates formed of relatively light gauge stainless steel, the plates being automatically self-tensioning as the cutter is pressed into engagement with the skin and but lightly tensioned when the driving motor is idling, to the end that wear on the cutter is minimized.

Another feature is the provision of shaving devices particularly well suited for women's use and for surgical purposes in removing the hair from various parts of the body preparatory to making an incision. The provision of a removable, simply constructed cutter head which can be conveniently sterilized also makes the device peculiarly suitable for surgical use.

Another feature of the invention is the use of a hair cutter which will cut either long hair or short hair or stiff hair or soft hair with equal expedition.

Another feature is an arrangement of shear teeth having interdental spaces of critical area as compared with the area of the teeth in order that the two sets of coating teeth may be in relatively "open" hair-receiving position over comparatively long periods of time. This is in direct contradistinction to the use of teeth which are in closed or partially closed position over relatively long time intervals and thereby block the entry of hair and retard the speed at which the cutter may be drawn over the skin and still operate efficiently.

The invention may be more fully understood from the following description in connection with the accompanying drawing wherein:—

Fig. 1 is a perspective view of an electrically operated razor embodying the invention.

Fig. 2 is an enlarged fragmentary sectional view taken approximately on the line 2—2 of Fig. 1.

Fig. 3 is a similarly enlarged view taken at right angles to Fig. 2 on the line 3—3 of Fig. 1.

Fig. 4 is a plan view of the movable cutter plate.

Fig. 5 is a similar view of the fixed cutter plate.

Fig. 6 is a considerably enlarged fragmentary plan view showing the teeth of the movable cutter plate.

Fig. 7 is a similar view showing the teeth of the fixed cutter plate.

Fig. 7a is a view similar to Figs. 6 and 7 but showing the two cutter plates superimposed.

Fig. 7b is an enlarged sectional detail on the line 7b—7b of Fig. 7a.

Fig. 8 is an enlarged transverse sectional view taken approximately on the line 8—8 of Fig. 7.

Fig. 9 is a view similar to Fig. 7a but illustrating a modification.

Fig. 10 is a reduced side elevational view of a modified form of cutter.

Fig. 11 is an enlarged plan view of the fixed cutter plate of this cutter.

Fig. 12 is a considerably magnified view through a section of skin showing the manner in which a hair projects through the skin pores without being attached to the skin at the surface, but being encircled by a small mound of flesh at the surface.

Fig. 13 is a view similar to Fig. 12 but illustrating the manner in which my improved razor de-

presses this mound and severs the hair below the top of the mound, and

Fig. 14 is a similar view showing the relationship of the remaining length of hair to the mound.

As suggested above, the reciprocating cutter may be manually operated if desired, or any suitable motive means may be employed for effecting reciprocation of the cutter. In Fig. 1, I have shown a typical motor casing member indicated generally at 10, this casing member including a portion 11 of uniform rectangular cross section extending throughout more than half of the length of the casing. The portion 11 constitutes a handle and beyond portion 11 all four sides of the casing taper as indicated at 12 toward the cutter head which is mounted on the flattened smaller end of the casing.

A lead wire 13 supplies current to an electric motor (not shown) housed within the casing.

The cutter head includes the movable cutter plate 14, stationary cutter plate 15 and keeper bar 16. The periphery of the head is smaller than the cross section of the main casing section 11 so that the head will not touch a supporting surface when the casing is laid upon such surface. With this in view it is of course desirable that the center of gravity of the motor be such as to cause the casing to rest on the rectangular section 11 so that there will be no tendency for the casing to rock on any of the shoulders defined by the juncture of the outer faces of section 11 and tapered faces 12. Thus the danger of bending the corners of the cutter head structure is avoided since no part of the cutter head will touch the supporting surface, regardless of which side the casing may be laid upon.

The details of the general arrangement of the two cutter plates and keeper appear more clearly in Figs. 2 and 3. A pair of headed studs 17 project from the end of the motor casing 10. These studs may be conveniently molded into the casing if desired, and between the studs is an opening 18 in the casing through which projects the end of an operating lever 19 engaging in a center opening 20 in the reciprocating cutter plate 14, riding near its side edges on rails 10a (Fig. 3) integral with casing 10. Lever 19 is motor operated in any suitable fashion and reciprocates the cutter 14 back and forth across the reduced flat end of the casing 10. In this movement the cutter is guided by the studs 17, being provided with elongated slots 21 to receive the studs. Plate 14 is of flat thin gauge stainless steel, suitably stamped and formed to provide the central aperture 20, the slots 21 and, along both sides thereof, a series of cutting teeth 22 which will be more fully hereinafter described.

The stationary cutter plate 15 is also of thin gauge stainless steel, preferably of the same gauge as the movable cutter 14. It is slightly bowed in cross section; it is provided with a pair of circular openings 25 to receive the studs 17 and may, if desired, be provided with a central opening 23 to provide clearance for the lever 19. The teeth 24 which are arranged at the sides of this cutter plate are longer than the teeth 22 (roughly twice as long) so that the free ends of the teeth 24 may be bent over as indicated at 24a (Fig. 8) to afford arcuate guard members protecting the skin from contact with the points of the teeth 22.

The head assemblage is secured in position by the longitudinally bowed keeper bar 16. This member is preferably of slightly heavier stock than the two cutter plates and is more rigid than the cutter plates. It is formed with a pair of

keyhole slots 26 therein which engage with the heads of the studs 17. In applying the keeper bar, a relatively light tension is exerted on the bowed stationary cutter plate 15 but this tension is insufficient to exert any material pressure on the over-riding teeth 24, 22 of the two cutter plates. This is important because by very lightly tensioning the plate 15, the major portion of the tension on the reciprocating cutter is applied by the pressure of the fixed cutter against the skin. Therefore when the razor is removed from the skin with the motor running, there will be very little wear on the cutter plates and very little load on the motor. By having plate 14 rest only near its edges on narrow rails 10a at the end of casing 10 the plate 14 responds readily to the tension exerted on plate 15.

In Figs. 6, 7 and 8 I have illustrated in greater detail the construction of the teeth of the two cutters. As seen in Fig. 6, the teeth 22 of the movable cutter blade are of generally triangular shape in plan view, tapering toward their outer ends. The teeth taper from top to bottom as indicated at 22a (Fig. 7b) so that their shearing edges are defined by two surfaces meeting at an acute angle.

The use of shearing teeth which are bevelled at their shearing edges is advantageous in that it eliminates any tendency to clog. The shearing principle does not depend upon a keen edge and in theory a right angle edge will shear satisfactorily but there is less tendency to clog the razor with hair when shearing plates having acute shearing angles are used.

I have found that the best results are obtained by making the interdental spaces between these teeth approximately twice as great in area as the teeth themselves. On the other hand the bent-over teeth 24 of the stationary cutter which likewise taper toward their outer ends and have tapering edge surfaces at 24b are preferably at least equal in area to the interspaces between them and are preferably of greater area than the spaces between them.

This relation of tooth size to the size of the interdental space is important. Insofar as teeth 24 are concerned, it is desirable that they be spaced apart merely a sufficient distance and be of sufficient depth to conveniently receive hair between them, without permitting the skin to enter between them and be pinched or cut. The teeth 22 need only be of sufficient width to insure the mechanical strength necessary to cut hair. The wider the space between the cutting teeth, the greater the opportunity for a hair to enter the space between adjacent teeth 24 without being blocked by the presence of a tooth 22. In other words, in normal reciprocation, the periods of time when spaces between teeth 24 are open to receive hair, are increased by decreasing the area of the teeth 22 with respect to the area of their interdental spaces. With the particular arrangement shown these spaces are fully open at both ends of the stroke of the movable plate 14 as will be apparent from Fig. 7a.

Fig. 9 illustrates a modification of the form of the teeth of Figs. 6 and 7. Here, teeth 32 of the fixed cutter corresponding to teeth 24 are similarly turned over at their ends and each has one substantially straight edge 33 and one relatively sharply inclined edge at 34. The relatively straight sides of the teeth 32 coat with the relatively straight sides of corresponding teeth 32a in the movable cutter plate. With this form of

tooth but little relative movement of the cutters is required to effect the shearing action.

Fig. 10 illustrates a modified type of motor casing 35 of generally L-shape and with a cutter head 36 secured on the flat inclined surface 37 at the shorter arm of the L. With this form of the invention, the cutter head will be provided with cutting means at only one edge. A typical stationary cutter used for this form of the device is illustrated in Fig. 11 and designated by the reference numeral 38.

In Fig. 12, the numeral 40 represents the human skin and 41 a pore in the skin. A hair 42 projecting from this pore is unattached to the skin at the surface but it is anchored by its root or follicle 43 which lies somewhat below the surface of the skin, at the base of the pore. The hair is encircled by a minute mound 44 of skin.

Fig. 13 shows the manner in which the rounded bent over ends 24a of the teeth 24 depress this mound and permit the hair to be cut at a point which is actually below the normal surface of the mound, Fig. 14 illustrating the severed hair and showing that a very close cut has been effected.

Neither ordinary safety razor blades, nor hollow ground razors, nor any other type of cutter mechanism with which I am familiar is capable of accomplishing such a close cutting action without the danger of scratching or abrading the skin or otherwise causing injury or discomfort.

Observation of the sets of cutter teeth of Figs. 6 and 7 indicate clearly that the severed lengths of hair will fall out from between the cutter teeth since there is no place else for them to go and there is no danger of the cutter teeth being clogged with hair. In practice I find that the cutter works equally well regardless of the stiffness or softness of the beard and regardless of the length of the beard. The cutter working very close to the skin severs the hairs close to or below the skin and they drop or are kicked out of the way by the further movement of the cutting teeth.

The present invention makes practicable the use of thin flexible stainless steel plates as shaving devices. In this connection it is to be borne in mind that most of the art of razor and blade making has been directed to the perfection of keen shaving edges, and stainless or rustless steel is inherently incapable of being worked and sharpened to produce such a keen edge. Insofar as prior developments of dry shavers are concerned, these devices have been generally of two classes,—either attempted modifications of standard hair clippers using heavy rigid shearing plates, hardened, ground and reduced to thin sections at the points (making it impossible to provide guard means such as those of the present invention), or the so-called dry shavers have been of such complex construction that stainless steel could not be satisfactorily worked into the odd-shaped parts required.

By the present invention using but three simple parts of thin relatively flexible stainless steel, I provide a rust-proof structure, and dispense with the hardening and plating operations with a consequent saving in manufacturing cost which for the first time makes it possible to sell a razor working on the shearing principle at a cost comparable to the cost of the ordinary safety razor and at a cost which is far below that of any so-called dry shaver or shearing device heretofore known.

The actual shaving elements themselves, that is the two cutter plates, may be manufactured

at but a fraction of the cost of previous shearing type shavers.

While I have shown no specific means for actuating the cutter structure either manually or from a motor, it will be understood that various types of motors might be utilized as well as the type illustrated in my copending applications Serial No. 746,500 filed October 2, 1934, and Ser. No. 757,755, filed December 17, 1934 and that various types of actuating mechanism for ordinary hair clippers might, with or without slight modification, be utilized for actuating the cutters. Such hand operated devices (capable of complete and expeditious sterilization) are particularly well suited for hospital use in close shaving long hairs from various parts of the body. Ordinarily such hairs do not grow in such profusion as the hairs on the face and they can be removed with sufficient expedition by a hand operated tool, whereas the motor operated type is found preferably for shaving a heavy beard due to the increased speed of operation of a motor actuated tool.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

Having thus described my invention, what I claim as new and desire to secure by Letters Patent is:—

1. A hair cutter including a pair of superimposed thin cutter plates, each having shearing devices at one edge, one plate having edge portions curved outwardly around the thickness of the shearing devices of the other plate to guard the skin against injurious contact with the shearing devices and to effect depression of the skin in advance of the cutting operation.

2. A hair cutter assembly including a pair of relatively thin gauge stainless steel plates arranged in superimposed relationship, each plate having shearing teeth at one edge, means for reciprocating one of the plates, said plates being substantially self-tensioning when pressed against the skin, the roots of the shearing devices of the two plates being at substantially equal distance from the lateral edge of the assembly.

3. A hair cutter including a pair of relatively thin gauge stainless steel plates arranged in superimposed relationship, each plate having shearing teeth at one edge, means for reciprocating one of the plates, one of said plates being bowed at its center, whereby it is self-tensioning when the edge of the plate is pressed against the skin, one plate having edge portions curved outwardly around the thickness of the shearing devices of the other plate to guard the skin against injurious contact with the shearing devices and to effect depression of the skin in advance of the cutting operation.

4. A hair cutter including a pair of superimposed thin cutter plates, each having shearing teeth at one edge, the teeth of one plate having their ends curved outwardly around the thickness of the teeth of the other plate to guard the skin against contact with the ends of the unbent teeth.

and to effect depression of the skin in advance of the cutting operation, and means for reciprocating one of the plates.

5. A hair cutter including a pair of relatively thin gauge stainless steel plates arranged in superimposed relationship, each plate having shearing teeth at one edge, means for reciprocating one of the plates, the teeth of the relatively fixed plate being bent into arcuate form just far enough beyond the ends of the teeth of the movable plate to prevent abrasion of the skin by the teeth of the movable plate.

6. A hair cutter including a pair of superimposed thin cutter plates, each having shearing teeth at one edge, the teeth of one plate having their ends curved outwardly around the teeth of the other plate to guard the skin against contact with the ends of the unbent teeth and to effect depression of the skin in advance of the cutting operation, and means for reciprocating one of the plates, the fixed plate being relatively bowed, means retaining the plates in superimposed position under light tension and said plates being capable of further tensioning by pressure of the fixed plate against the skin.

7. A hair cutter including a handle, a flat support member at one end of the handle, a thin flat cutter plate reciprocable over the face of the support, studs rising from the support and guiding the movement of the cutter plate, a cooperating fixed cutter plate and a keeper removably held in position by the studs and pressing the fixed cutter plate against the movable cutter plate, said plates having coacting shearing teeth at at least one edge, the relatively fixed plate being transversely bowed, whereby the tension between the cutter plates may be increased by pressing the edge of the skin-contacting plate against the skin, the teeth of the bowed plate extending substantially the entire length of the teeth of the movable plate and having protruding ends curved around the teeth of the movable plate to afford guards and present rounded skin engaging surfaces.

45. 8. A hair cutter including a handle, a flat support member at one end of the handle, a thin flat cutter plate reciprocable over the face of the support, studs rising from the support and guiding the movement of the cutter plate, a cooperating fixed cutter plate and a keeper removably

held in position by the studs and pressing the fixed cutter plate against the movable cutter plate, said plates having coacting shearing teeth at at least one edge, the relatively fixed plate being transversely bowed, whereby the tension between the cutter plates may be increased by pressing the edge of the skin-contacting plate against the skin, the teeth of the bowed plate extending substantially the entire length of the teeth of the movable plate and having protruding ends curved around the teeth of the movable plate to afford guards and present rounded skin engaging surfaces, both cutter plates being formed of relatively light gauge stainless steel.

9. A cutter including a pair of relatively reciprocable superimposed cutter plates, each plate having shearing teeth at one edge thereof, slideable against the shearing teeth on the adjacent plate, one of said plates being relatively fixed and the teeth thereof being adapted to engage the skin during the cutting operation, the teeth of said plate having areas at least equal to the interdental spaces at the edge of the plate, the teeth of the movable plate having areas approximately half as great as the areas of the interdental spaces in the edge of such plate, and the entire length of the teeth on the movable plate engaging the teeth of the fixed plate in the course of the operation.

10. A cutter including a pair of relatively reciprocable superimposed cutter plates, each plate having shearing teeth at one edge thereof, slideable against the shearing teeth on the adjacent plate, one of said plates being relatively fixed and the teeth thereof being adapted to engage the skin during the cutting operation, the teeth of said plate having areas at least equal to the interdental spaces at the edge of the plate, the teeth of the movable plate having areas approximately half as great as the areas of the interdental spaces in the edge of such plate, the teeth of the fixed plate extending substantially the entire length of the teeth of the movable plate and having protruding reversely curved arcuate ends disposed beyond the ends of the teeth of the movable plate and adapted to engage the skin, and the entire face area of the teeth on the movable plate engaging the teeth of the fixed plate in the course of operation.

JOHN A. HANLEY. 50
